United States Patent Office

Des. 181,036
Patented Sept. 24, 1957

181,036

TYPEWRITING MACHINE

Paul A. Braginetz, Hartford, Conn., assignor to Underwood Corporation, New York, N. Y., a corporation of Delaware

Application October 11, 1956, Serial No. 43,329

Term of patent 14 years

(Cl. D64—11)

The figure is a front perspective view of a typewriting machine showing my new design from the right-hand side thereof.

The machine when viewed from the left-hand side, is a substantial mirror image of the described figure. The rear wall of the machine is substantially planar and plain.

The dominant features of my design reside in the portions of the machine shown in solid lines.

I claim:

The ornamental design for a typewriting machine, as shown and described.
